United States Patent Office.

CYRUS W. STROUT, OF HALLOWELL, MAINE.

Design No. 3,753, dated November 16, 1869.

DESIGN FOR FLOOR OIL-CLOTH.

The Schedule referred to in these Letters Patent and making part of the same.

To all whom it may concern:

Be it known that I, CYRUS W. STROUT, of the city of Hallowell, in the county of Kennebec, and State of Maine, have originated and designed a new Pattern for Floor Oil-Cloths, of which the following is a full, clear, and exact description, reference being had to the accompanying drawing or printing, making part of this specification.

The drawings, printed in colors on oiled paper, represent a complete design for floor oil-cloth.

This design, when repeated or reversed on the ends and sides, form irregular block-work squares, running diagonally across the pattern.

The printed drawings represent more fully, clearly, and exactly than any written description can do, the nature and extent of my invention.

Claim.

What I claim as my invention, and desire to secure by Letters Patent, is—

The design for floor oil-cloth above described and shown.

CYRUS W. STROUT.
